UNITED STATES PATENT OFFICE.

ALFRED L. STEVENS, OF DAYTON, OHIO, ASSIGNOR OF TWO-THIRDS TO JOHN M. PHELPS AND CHRISTOPHER W. UTHBROK, OF SAME PLACE.

CAN-LABELING MACHINE.

SPECIFICATION forming part of Letters Patent No. 517,898, dated April 10, 1894.

Application filed October 21, 1893. Serial No. 488,834. (No model.)

To all whom it may concern:

Be it known that I, ALFRED L. STEVENS, of Dayton, county of Montgomery, State of Ohio, have invented a new and useful Improvement 5 in Can-Labeling Machines; and I do declare the following to be a full, clear, and exact description of the invention, such as will enable others skilled in the art to which it appertains to make and use the same, reference being had 10 to the accompanying drawings, and to the letters and figures of reference marked thereon, which form a part of this specification.

This invention relates to improvements in can-labeling machines.

15 The object of the invention is to simplify the mechanism and reduce the expense of making a machine of the class named, while the efficiency thereof is proportionately increased.

20 To these ends the improvements consist in providing an incline way in which two separate paste receptacles and their appliances are located; one to give the initial, and the other the final application of paste to the can, while said can is gravitating down the incline; and further, in a label holder of peculiar form with adjunctive devices, also located on said incline between the paste stations and in the path of the can, and other 25 features of novelty that will be fully described in the specification and mentioned in the claims.

In the annexed drawings which are hereby made a part of the specification, and upon 30 which similar characters of reference denote corresponding parts, Figure 1 is a plan view of the inclined way and the mechanical elements operating in conjunction therewith, the lower end broken off; Fig. 2 a side elevation 35 of the median portion of the inclined way, one side being removed to exhibit the location and arrangement of the labeling parts; Fig. 3 a side elevation exhibiting the lever and ratchet mechanism, the dotted lines show 40 the label holder lowered to a position to take on labels; Fig. 4 a vertical section on the line $x-x$ of Fig. 3; Fig. 5 an enlarged side elevation with ends broken off, showing the ratchet mechanism; Fig. 6 a view of the lower end of 45 the inclined way, from beneath; Fig. 7 a detail, detached side elevation of one of the paste receptacles, a side thereof being re-

55 moved to exhibit the mounting of the lower roller; Fig. 8 a detached, detail plan view of one of the paste receptacles; Fig. 9 a detail detached side elevation of one of the plates that inclose the side of the labels; Fig. 10 a sectional view of a portion of one of the sides of the inclined way, showing the means for adjusting the adjustable plate inclosing one 60 of the sides of the labels; Fig. 11 enlarged detail detached front and edge views of the roller scraper.

1 indicates side pieces joined by bottom brace pieces 2, 3, and 4 all of which constitute an inclined way, having for its support, standards 5—5 any suitable number of which may be employed, and their length such that will effect an incline of the way substantially as shown in the drawings, which enables the 65 can to roll down the way at a suitable rate of speed for the purposes in hand.

The paste receptacles of which there are two, 6 and 7, are located as shown in Fig. 2; the object of having two paste holders, and 70 their particular location will be mentioned hereinafter; each of these receptacles is provided on its inner sides with ledges 8, of curvilinear form, upon which the journals of rollers 9 and 10 are mounted, and which rollers are provided with a number of teeth near 75 their ends, projecting from the circumference, that engage with rollers 11 and 12 journaled in the sides of the inclined way; the latter rollers are provided with a yielding or 80 pliable surface, with which the teeth on rollers 9 and 10 engage, and are thereby rotated, the manner of mounting the latter rollers being such that will maintain them in normal 85 contact with the rollers 11 and 12 by force of gravity, and said rollers 9 and 10 have the two-fold function of agitating or mixing the 90 paste, and applying the same to rollers 11 and 12. The pasting surface of roller 11 terminates at both ends about a half an inch or so 95 shorter than the length of the cans, the object of this construction is to prevent the application of paste to the extreme ends of said cans for the reason that the pressure would squeeze the paste over the ends of the cans 100 which would interfere with the efficiency of the work. It will be noted, that the diameters of rollers 11 and 12 vary, and that the former roller rotates in the paste; this con-

struction and arrangement are essential, for the reason that it is necessary to apply paste to a greater area of the can's surface in the initial application, while a less quantity of 5 paste is required for the final end.

13 is a paste scraper mounted transversely adjacent to the surface of roller 11, with ends 13^a at right angles to extend over the ends of said roller, to prevent the accumulation of an 10 excess of paste on said roller.

14 and 15 are ratchet wheels keyed to one end of the shafts or rollers 11 and 12 on the outside of the inclined way.

16 and 17 are ratchet plates pivoted to the 15 horizontal bar 18 and having one end (19) bent outwardly at right angles to engage with the teeth of said ratchet wheels; the bar 18 is slidingly mounted in guides 20 and has a pivotal connection at its forward end 20 to an upright lever 21 which lever is reinforced on either side by plates 22. This lever has its fulcrum on a horizontal arm 23 fast at one end to an upright 24, of which there are two—one on each side of the inclined way.

25 is an upright lever having a fulcrum on a horizontal bar 26 loosely journaled in uprights 24.

27 is a link, fast to one end of the bar 26, 30 and the other end of said link having a pivotal connection with plate 28 to which the lever 21 is attached. At the lower end of lever 25 is rigidly attached a plate 29 the function of which is to allow the cans to travel at 35 the proper time, or prevent them from traveling down the incline way, which is done by moving the lever 25 forward or backward as the case may be, by the hand; this operation also actuates the ratchet mechanism through 40 the movement of the bar 18 as appears in full and dotted lines in Fig. 5, and which further revolves the paste rollers as will be readily understood.

30 represents the label holder hinged at one 45 end to the inclined way, and having a curvilinear bed or raised portion 31 inclining rearwardly, upon which the labels 32 are placed, and an inclined stop or rest 33 at its rearward end against which the lower ends of the labels 50 rest.

34 is a weight hinged to the rest 33 and adapted to press upon the top of the labels to keep them smooth and in position. The location of the label holder with reference to 55 the initial paste roller 11 is such that the pasted portion of the can will come in contact with the label a sufficient distance away from the extreme front edge thereof, to prevent the paste from oozing from between the 60 can and label. It is understood that were paste permitted to ooze from beneath the label, the accumulation of paste on the bed of labels and in the track of the cans, would in time, retard the operation of labeling. The 65 avoidance of this objection is an important feature of the present invention.

It will be noted in Fig. 2 that the front ends

of the labels are elevated to a horizontal plane by reason of their resting on the bed 31 and that the front and rear edges of the pack incline by reason of the rear ends resting against the rest 33; this arrangement is important as it enables the gravitating cans to take up only one label at a time, without applying the paste to the edges of any of the other labels the 75 portion of the can having the initial application of paste, coming in contact with the surface of the label to a sufficient extent to cause said labels to adhere thereto.

35 represents stops or guides journaled in 80 the sides of the inclined way, having on one end a pin projecting at right angles over the pack of labels and into a portion of the labels, the object of which is to assist in preserving the labels in a proper condition to be taken 85 up by the can, and to prevent the possibility of the engagement of but one at a time.

At the front end of the label holder an arm 36 is attached to the projecting end of which a cable or rope 37 is secured; this rope surrounds a pulley 38 journaled in the sides of the inclined way, and has a weight 39 attached to the other end, the effect of this weight is to normally elevate the label holder 95 on its pivot and thereby maintain the labels in contact with the stops 35 and in the path of the cans.

40 and 41 indicate plates having lateral pins on their sides by which they are attached to the inner sides of the inclined way so that 100 they inclose the sides of the labels; these plates might be said to form the sides of the label holder, inasmuch as they occupy a relative position thereto; the mounting of plate 40 is rigid, but that of plate 41 is adjustable 105 as shown in Fig. 10, by providing a spring metal plate 42 secured at one end to the side of the inclined way; this plate may be adjusted by means of a screw 42'.

43 and 44 are tracks upon which the cans 110 travel, the former track commences at the upper end of the incline way and carries the cans over the first pasting station where they take on a sufficient amount of paste to take up the front end of a label as is shown in 115 Fig. 2; after leaving the bed of the labels, the upper edges of the plates 40 and 41 form a track for the cans until track 44 is reached which carries them over the second pasting 120 station; the second application of paste is to secure the lower or overlapping end of the label and thus completely apply it,—it being understood that the first application of paste is to secure the initial end of the label. It will be noted that the second paste receptacle 125 is located with reference to the time it takes the can to present the initial end of the label to paste roller 12. After the can has received the entire label, the track 44 delivers it to an exit track constructed of a series of ropes 45 secured longitudinally in the lower end of the inclined way; these ropes present a yielding 130 surface and support to the cans, and exert a requisite amount of pressure thereon to in-

sure a perfect adherence of the labels; any unnecessary slack of said ropes may be taken up by adjusting the transverse bar 46 to which one end of the ropes are secured, by means of the bolts 47 fixed to the lower extremity of the way, and upon which the bar 46 is mounted.

In Fig. 2,—48 represents a can having just taken up a label; 49 is a pressure belt supported upon uprights 50 and 51.

Fig. 3 shows in dotted lines cans traveling down the incline. Finally, to prevent any paste from accidentally flying on the edges of the front ends of the labels I suspend an apron 52 of any suitable material, just below the first paste receptacle, this apron is somewhat similar in form to the plate 29 and is permitted to freely vibrate as the cans pass.

Having fully described my invention, I desire to claim as follows:

1. In a can-labeling machine, the combination with the inclined way herein described; of paste receptacles with ledges 8, the paste rollers 9 and 10 having circumferential teeth near their ends, and bearings on the ledges 8, the paste rollers 11 and 12 by which the rollers 9 and 10 are revolved, and the ratchet mechanism by means of which the rollers 11 and 12 are revolved.

2. In a can-labeling machine, the combination with the inclined way; of a label holder having one end pivoted to the way, and the other end free to be lowered or raised, paste receptacles, one above and one below said label holder for adhering the initial and final ends of the labels to the cans, the paste rollers 9 and 10, and 11 and 12, ratchet wheels rigidly mounted on the journals of rollers 9 and 11, the horizontal sliding plate bar 18 having one end pivoted to the vertical lever 21, the plates 16 and 17 pivoted to the bar 18, and adapted to engage with the ratchet wheels, and means for operating the lever 21 whereby the bar 18 is moved and the ratchet mechanism actuated, substantially as herein described.

3. In a can-labeling machine the combination of the inclined way, the pressure belt 49 mounted over said incline, a label holder piv-

oted at one end, to said incline, the bed of 50 said label holder having a curvilinear form whereon the front ends of the labels lie in a horizontal plane, paste receptacles located beneath the incline, and at both ends of the label holder, the rollers 11 and 12, and the 55 rollers 9 and 10, the latter having peripheral teeth to engage with the former, whereby paste is applied to the cans in a manner to prevent said paste from oozing from beneath the label, substantially as described.

4. In a labeling machine, the combination with the inclined way; of a curved label bed having one end pivoted to the inclined way, the curvature of said bed being such that presents one end of the labels in a horizontal 65 position to be taken up one by one by the gravitating cans, the guides 35 with pins penetrating said labels to control the removal thereof, paste receptacles located above and below the label holder and beneath the inclined way, pasting rollers mounted in said receptacles in the path of the cans, and lever and ratchet mechanism for rotating said rollers, substantially as described.

5. In a can labeling machine, the combination with the inclined way; of a curved label holder having one end hinged thereto, the curvature of the bed of said holder being such that will present the initial end of the labels to the cans, on a horizontal plane, so that said 75 cans may come in sufficient contact therewith, the guides 35 having pins adapted to penetrate said labels and thereby control their removal, the side plates 40 and 41 inclosing the sides of the labels, the latter plate being adjustable, whereby said plates are adapted to inclose labels of different widths, paste receptacles located beneath the inclined way, above and below the label holder with pasting rollers mounted therein, and lever and ratchet 80 mechanism for rotating said rollers, substantially as described.

In testimony whereof I have hereunto set my hand this 29th day of September, 1893.

ALFRED L. STEVENS.
